(57) **CLAIM**

We claim the ornamental design for a toy element, as shown and described.

DESCRIPTION

1. Toy element

1.1 is a top, left side perspective view of a toy element showing my new design;

1.2 is a top, rear perspective view thereof;

1.3 is a left side view thereof, the right side being identical;

1.4 is a top view thereof;

1.5 is a bottom view thereof.
